UNITED STATES PATENT OFFICE

2,451,482

SPARKING DEVICE

Charles R. Flint, La Porte, Ind., assignor to The
De Luxe Products Corporation, a corporation of
Indiana

Application March 22, 1945, Serial No. 584,097

3 Claims. (Cl. 123—148)

1

This invention relates to a sparking device. Internal combustion engines consist of one or more cylinders which are individually fired when the fuel within them has been properly compressed. In the usual automotive engine the firing is done by means of a spark plug or other sparking device which is actuated by an intermittently actuated spark coil suitably timed and connected seriatim to the various plugs. In the Diesel engine the firing is accomplished without a spark plug by the compression itself.

I have now discovered that improved firing may be obtained, either in the internal combustion engine or in the Diesel engine. This may be accomplished in the spark fired engine by energizing the spark plug or other device with a high-voltage low-amperage charge insufficient in quantity to cause firing. In the Diesel where there is no such sparking device, a similar effect may be accomplished by providing sparking means similarly actuated.

The precise reason why such energization should operate to improve firing is not understood. A physical disturbance is created by the static charge in the neighborhood of the spark members, and it is possible that this disturbance creates a turbulence of value in the combustion of the gases. It is also possible that there may be a corona discharge effect having some ionizing value. Energization immediately prior to firing is most beneficial, but in some cases it may be desirable to energize all non-firing plugs or sparking devices in various cylinders of multicylinder engines simultaneously.

Various means for accomplishing this result are illustrated in the drawings, in which Fig. 1 is a diagrammatic view of one form of the device; Fig. 2 is an enlarged fragmentary view of the condenser tube portion of Fig. 1; Fig. 3 is a sectional view taken on the lines 3—3 in Fig. 2; Fig. 4 is a diagrammatic view of a modified structure; Fig. 5 is a top plan view of a distributor modified to permit operation of the present invention; Fig. 6 is a sectional elevation, broken away, of a further modification; and Fig. 7 is a plan view of a modified distributor.

In the form of the invention shown in Figs. 1, 2 and 3, the multicylinder, two stage motor, having cylinders equipped with the usual inlet and exhaust valves and spark plugs are not shown. The invention operates best with the standard form of cylinder in which the spark plug is in a small pocket laterally offset from the cylinder proper and within which pocket most of the compressed gases are forced at the time of firing.

2

The device comprises the usual rotor 10 located in the distributor 11 and energized by the customary spark coil, not shown. The rotor successively contacts the firing segments 12, each connected to one cylinder of the engine at the spark plugs 13.

Likewise connected to the rotor, preferably through a suitable adjustable spark gap 18, is a small metal rod 14, which is mostly enclosed within a tube 15, suitably of glass or other insulator. The rod 14 may be spaced from the tube by insulating spacers 16 of rubber or the like. Spaced along the tube are metal bands 20, spaced from each other and each connected to one spark plug 13. For example, band 20a is shown connected to spark plug 13a, the second in line, and fourth in firing order.

The rod may suitably be $\frac{1}{8}$ inch in diameter, the tube $13\frac{1}{4}$ inch internal, and $15\frac{1}{4}$ inch external diameter. The bands may be one inch wide, spaced one inch apart and of any suitable thickness. A few thousandths of an inch is sufficient. They are also sufficiently spaced at the ends from the rod 14 to avoid spark leakage.

25 In operation of this form of the device, the rod 14 is energized each time the rotor is energized. This induces a charge of substantially the same voltage, but of very low amperage, in the bands 20, which charge is communicated to each plug.

30 In the form shown in Fig. 4 the structure of the rod 14, and the bands 20 is the same as in Figure 1, as is the connection of bands to the spark plugs. Instead of connecting the bar to the spark coil, however, it is connected to the contact 25 of the intermittent sparking device 26, which may be of the familiar type formerly employed in Ford cars. This device is adapted to produce a charge like that of the spark coil but much more rapid. A suitable grounded spark gap 60 should be included in the system.

40 In the device shown in Figure 5, the bar 14 is eliminated, or replaced by a corresponding member 30 carried by the distributor itself. The member 30 comprises a wire 31 connected to the rotor 10 and branched on both sides to form a W-shape. The wire 31 is encased in an insulating (glass) tube 32 carried by the distributor. It will be observed that the wire 31 is always immediately adjacent, but spaced from, each of the non-firing ignition points, whenever a cylinder is being fired.

45 In this way, the same form of high voltage, low amperage charge is imposed upon the non-firing points as in the other examples.

50 In Fig. 6 a further modification, applicable to

each of the other forms, is illustrated. In this form, the bar 14 is connected electrically to the screw 40 which has a depending wire or rod 41. The screw 40 is held in the union 42, which may be of metal or plastic or other material. If plastic, or other insulating material is used, a connection is provided between the bar 14 and the screw 40. Surrounding the wire 41, and depending from 10 42, is a glass, or other insulating tube 43. This is connected at the bottom with the nipple 44, which in turn is open to the intake manifold, not shown. Mounted in the base of the tube, and extending through the nipple 44 is a wire 45, connected to the spark coil of the engine, or to a separate coil as shown either in Fig. 1 or 4. Both connections of the glass tube are airtight. It is also preferred to close the far end of the bar 14 with a cap 47.

In operating this form of the device, a variable spark gap is provided between wires 41 and 45, the length of which may be altered by movement of the screw 40. The adjustment of this gap is made such that when the engine is operating under load the spark will not bridge the gap, whereas when the vacuum is high sparking will occur. This avoids possible backfiring under heavy throttle, but does not eliminate operation of the bar even when the spark is not bridging the gap, although the extent of static energization is much reduced.

In the form of device shown in Fig. 7, the rotor 10a is provided with an adjustable arm 10 held in place by the set screws 71, about which it is slidably mounted. The arm 10 is pointed ahead of the rotor in the direction of its movement and has the effect of statically energizing the next succeeding segments 12 whenever the adjacent segment 12 is being energized. If desired the arm may extend to only one segment 12.

The form of device shown in Figure 4 is adaptable not only to single and multiple cylinder spark fired engines, but may also be employed in Diesel type engines, whether single or multicylinder.

In a Diesel engine a conventional timing device such as is used in the automobile may be employed to produce the electrical field adjacent or even around the discharge nozzle within the combustion chamber. This may be done by providing an insulated electrode within the combustion chamber.

The foregoing detailed description has been

given for clearness of understanding only, and no unnecessary limitations should be understood therefrom.

What I claim as new and desire to secure by Letters Patent is:

1. In a distributor, a member carried by the rotor, and having an electrically conductive arm in closely spaced relationship to at least one of the distributor ignition points other than the point being contacted by the rotor, said member being electrically connected to the spark coil.

2. A distributor as set forth in claim 1, in which the member is in spaced relationship to all of the distributor ignition points except the point being contacted by the rotor.

3. In a multicylinder, spark-fired, internal combustion engine having an intake manifold normally under substantial vacuum, and having a sparking device in each cylinder actuated by a spark coil, means for electrically energizing at least one sparking device by a separate electrical impulse insufficient to fire the same prior to firing thereof, said means including a distributor electrically connected to a spark coil which may be the aforesaid spark coil, a plurality of metal members electrically connected to the distributor and energized therewith, with the metal members being connected individually to the sparking devices, there being an air gap in the connection between said metal members and the spark coil with said air gap being normally bridged by the electrical impulses thereto, and means for varying the absolute pressure about said gap in correlation with the absolute pressure in the intake manifold of the engine.
